UNITED STATES PATENT OFFICE.

ISIDOR J. KUSEL, OF CHICAGO, ILLINOIS, ASSIGNOR TO STRONGHART COMPANY, OF CHICAGO, ILLINOIS, A CORPORATION OF ILLINOIS.

SMALL BANK.

1,369,674.

Specification of Letters Patent. Patented Feb. 22, 1921.

Application filed September 4, 1917. Serial No. 189,530.

To all whom it may concern:

Be it known that I, ISIDOR J. KUSEL, a citizen of the United States, residing at Chicago, in the county of Cook and State of Illinois, have invented a certain new and useful Improvement in Small Banks, of which the following is a full, clear, concise, and exact description, reference being had to the accompanying drawings, forming a part of this specification.

My invention relates to small banks for coins and other valuables.

The principal object of the invention is to provide a simple, practical and inexpensive construction of bank of the kind specified.

Another object of the invention is to simplify the construction and adapt it especially for manufacture by machinery, thereby increasing the speed of production and decreasing the cost thereof.

In the accompanying drawings Figure 1 is a vertical section of a small bank embodying my present invention;

Fig. 2 is a view of the inside of the cover of said bank with a portion of the same shown in cross section for convenience of illustration;

Fig. 3 is a perspective view of the coin receiving mechanism which is applied to the inner side of the cover;

Fig. 4 is a cross section showing a portion of the cover of said bank;

Referring to the drawings I show a bank consisting of a lower or body portion 1 and an upper portion or cover 2. The body portion 1 is preferably made of metal and in the form shown it has a cylindrical wall 1^a and a flat bottom 1^b. The cover 2 is preferably made with a metal cap 2^a with the annular flange 2^b which fits within the upper portion of the cylindrical wall 1^a of the body 1. Said top is also preferably provided with a covering consisting of a metal shell 4 and a layer 5 of celluloid fitted closely thereon and held in position by having its edge folded back and crimped underneath as shown at 5^a. The celluloid or similar material may be used for advertising matter or otherwise. In this construction it may be readily applied to the cap member 2^a and will be held properly in position.

The base or body 1 is preferably provided with a coin slot 6, through which coins

may be inserted, and is also preferably provided with an opening 7 into and through which bills may be inserted, whereby the bank may serve both for coins and bills.

The base 1 and top or cover 2 are provided with means by which they may be locked together so that the bank may not be opened except at the proper time by the proper person. To such end the base 1 is provided with a punched in portion 8 and the top 65 2 with a corresponding indentation 9 which may engage one another to lock the side of the bank near the coin slot 6. At the other side of the bank the cover is provided with two prongs 10—10, Fig. 2, preferably made 70 by punching out side portions of the rim or flange 2^b, and the base 1 is provided with a locking mechanism adapted to engage the prongs 10 and thereby lock the cover 2 in position. The locking mechanism comprises two pivoted members 11 and 12 which are pivotally mounted on a tubular member 13 providing the bill aperture 7. These members are arranged so that they may be actuated by a key inserted through a key-hole 15 in the base 1. Inasmuch as this locking mechanism is made the subject matter of an application filed by me December 6, 1916, Serial No. 135,374, it will not be described in further detail herein.

I also desire to provide an arrangement by which the coins inserted through the coin slot 6 may be automatically prevented from falling or being shaken out of such slot. This involves a platform 16 arranged so that it will lie substantially in alignment with the lower edge of the slot 6 so that it may receive the coins inserted through the latter and also arranged to tilt or swing so that said coins may slide off from it into the interior of the bank. To such end the platform 16 is provided with upwardly extending side members 17 which are pivoted at 18 to the downwardly extending side members 19 on a clip 20 which is secured to the top or cover 2. The platform 16 is provided with an upwardly inclined end portion 21 located substantially in front of the coin slot 6 so that normally said portion 21 closes said slot but a coin when inserted may 105 strike against the inclined surface of said portion 21 and thereby cause said platform to slide downwardly and permit the coin to come into position on the platform 16, after which a further tilting motion of the 110

platform due to the weight of the coin will drop the latter into the bank. The clip 20 is preferably secured to the metal wall of the top or cover 2 by means of a fastener 22 conveniently made by punching a portion of the top wall of the cap 2^a downwardly so that an edge portion 23 of said clip may be pushed in between said portion 22 and the wall surface. The clip 20 is further held by means of a second fastening device 24 also conveniently made by punching downwardly a portion of the metal top of the cap 2^a, and the clip 20 is provided with an aperture 25 through which said fastening device or prong 24 may be passed. The clip 20 is preferably provided with a formed up ridge 26 with which the fastener or prong 22 may be engaged to secure a firmer grip. The pivotal connection between the platform 16 and side walls 19 of the clip 20 is preferably made by eyelets 27—27 passing through said members 19 and 17.

As a further preventive of the escape of coins, a wall 28 is preferably arranged in position in front of the inclined member 21, said wall 28 being conveniently formed by punching down a portion of the flat base portion of the clip 20. In such case said wall 28 is preferably provided with a bent or turned portion 29 to more effectually engage the coins.

It will be seen that this construction permits the various parts to be made in very few pieces and to be punched up of sheet metal which greatly reduces the cost and greatly facilitates production.

It will be understood that changes and modifications may be made without departing from the spirit of the invention.

What I claim is:

1. A small bank having a coin slot and a pivotally supported tilting platform having a bent end located adjacent to the coin slot so as to open and close the same by the tilting motion of the platform, and a clip secured to the top of the bank and serving as a means for pivotally supporting said tilting platform, said clip being provided with a downward extension located between the pivotal mounting of the platform and the coin slot, and adapted to assist the aforesaid control of the coins.

2. A small bank having its top wall constructed by a plurality of layers of material, said bank also having a coin slot located below said top wall, a clip secured to said top wall by means of prongs formed by punched out portions of the innermost layer of said top, said clip having its top provided with apertures through which said prongs are extended, and a tilting platform having upwardly extending sides pivotally connected with downwardly extending sides on said clip, said platform having one of its ends adjacent to said coin aperture and provided with a bent end for the purpose of permitting the insertion of coins, but preventing the escape of the same, and said clip being provided with a downward extension in the rear of said bent end to co-operate in such control of coins.

In witness whereof, I hereunto subscribe my name this 16th day of August, A. D. 1917.

ISIDOR J. KUSEL.
